UNITED STATES PATENT OFFICE.

JAMES T. FENTON, OF SALT LAKE CITY, UTAH.

DRY-CLEANING SYSTEM.

Application filed October 11, 1921, Serial No. 507,017. Renewed November 19, 1927.

The present invention has for its object, 5 economizing in dry cleaning of textile materials, such as soiled garments and the like, while making the cleaning process more complete and more effective, and will substantially do away with the necessity of distilling the dry cleaning fluid. The invention involves both the process and the apparatus for accomplishing the stated results.

10 In accordance with the present invention, the textile material, such as soiled clothing, is put into a washer preferably a rotary drum washer of any of the well known types which are on the market. Into this washer 15 is run a cleaning fluid, such as gasoline, naphtha or other light hydrocarbon solvent, or mixtures of such materials with components capable of reducing the inflammability thereby, such as carbon tetrachloride, chlorinated ethanes, chloroform or other like materials. Preferably a continuous stream of the 20 cleansing fluid runs into the washer, while a corresponding stream flows out of the washer, to a purifying system. It is advisable to so regulate the inlet and outflow 25 of cleansing liquid as to maintain a sufficiently uniform quantity of cleansing fluid in the washer. The dirty cleaning fluid drawn out is preferably run first through a 30 storage tank for equalizing the flow of the liquid through the system. From the storage tank the soiled liquid is run into an agitator tank in which it is agitated with a solid material having good adsorbing properties, for 35 example, fuller's earth. The liquid after being thoroughly agitated with the adsorbing material is then separated from the adsorbing material and from the adsorbed impurities which are taken up by the adsorbing 40 material. The purified liquid is then run back into the washer, making the process cyclic. It is not necessary in ordinary washing operations to go to the expense of distilling the washing liquid, which operation 45 entails considerable expense for both apparatus, heat and attendance. It is, of course, understood that additional quantities of the 50 cleansing fluid may be introduced from time to time, to make up for small mechanical losses and losses by evaporation.

In the accompanying drawings, I have shown more or less diagrammatically, apparatus within the scope of the present invention, for carrying out the process above 55 briefly described. In said drawings Fig. 1 is a side view, partly in section, of apparatus

which is suitable for use in the process. Fig. 2 shows a preferred form of extractor basket and a canvas filter for the same. Fig. 3 shows the location of an inner filter bag within the canvas filter shown in Fig. 2, Fig. 3 also shows riffles and the cycloid distributor located within the inner filter bag. Fig. 4 is a plan view of the device shown in Fig. 3. Fig. 5 is a plan view of the cycloid distributor shown in Fig. 3. Fig. 6 shows one form of attachment of riffles to the inner filter bag. Fig. 7 shows one construction of the cycloid distributor illustrated in Fig. 5. Fig. 8 shows a preferred construction of an 60 automatic regulated feed for the clarifying material, to the agitator tank and Fig. 9 shows a detail of construction in connection with the said feed mechanism, Fig. 9 being a view of the parts in question looking from 65 a plane indicated by the lines 9—9, looking in the direction of the arrows.

In carrying out the process of the present invention, the soiled clothing or other material to be cleaned is put into the washer 20 which in the construction shown has an inner 70 perforated drum 21, mounted upon an axle 22, rotated by suitable means, for example, the pulley 23. Gasoline or other cleaning liquid is fed to the washer, preferably in a 75 continuous stream, by pipe 24, provided with a valve 25. The rotation of the drum 21 causes the clothing to be tumbled about with the gasoline, whereby the gasoline absorbs and dissolves the greases, oils and other materials soluble in gasoline, and also on account of this action, the solid dirt is so loosened that it readily goes into suspension 80 in the gasoline. The liquid is drawn out from this tank, preferably in a continuous 85 manner, through pipe 26, provided with a valve 27, leading to a pump 28. The said pipe is also provided with a by-pass 29 carrying a valve 30 and also a float-regulated valve 31. Attached to the lower part of the 90 washer is a pipe 32 connected to a stand pipe 33 carrying a float 34. This float 34 on account of the connections 35, 36 and 37 controls the valve 31 so as to maintain in 95 the washer tank, a substantially uniform 100 depth of gasoline, indicated largely by way of example, by the line 38. The liquid is brought up by pump 28 and pipe 39 into the tank 40. The liquid leaves the tank 40 by pipe 41 provided with a valve 42 and with 105 a float regulated valve 43. The liquid flows through the pipe 41 into the spout 44 of the 110

hopper 45. The spout 44 discharges into the upper part of the agitator. From the receptacle 46 is fed a solid adsorbing material through the spout 47 into the hopper 45, this being fed for example by the worm 49 operated by a pulley 50. The mixture of gasoline and solid in the agitator tank is agitated by means of an impeller 51 preferably located in the lower end of the central compartment 52. This central compartment or tube is held in place by the braces 53, which braces do not completely fill the cross section of the agitator tank, outside of the central pipe or casing. This central pipe is preferably also provided with perforations as shown at 54 near its lower end, in order that some liquid can be drawn in through these perforations and forced downwardly by the screw propeller 51, in order to give an additional amount of circulation and agitation in the bottom of the receptacle, and also in order to provide adequate circulation in the agitator tank, should the level of liquid therein fall below the top of 52.

25 The liquid level of the agitator tank is preferably maintained substantially uniform, by means of the float 57 and its connections 58, 59, 60 and 61, controlling the liquid valve 43. The propeller 51 is rotated 30 at a suitable rate of speed by means of the shaft 62 on which said propeller is mounted, this shaft being driven from a pulley 63.

35 The liquid carrying the adsorbing material such as fuller's earth, together with whatever the same has taken up in the agitator tank is fed through pipe 70 controlled by valve 71 into a centrifugal separator 72. Here all solid material is separated from the gasoline, the latter flowing out through pipe 40 74 past check valve 75 and valve 25, through pipe 24 into the washer 20.

45 The gasoline as above stated removes the greases and oils and also the solid dirt from the cloth or other material being washed in the washer 20. When this liquid is agitated with fuller's earth or like adsorbing material in the agitator tank, the fuller's earth will adsorb and take up both the solid impurities and the oils and greases from the 50 gasoline, leaving the said gasoline completely purified, and when the solid material has been separated from the gasoline in the separator 72 the said gasoline is entirely clean and may be then run back into the washer 55 20. The purification of the gasoline in this manner is so complete that I have been able to wash white clothing in gasoline which has previously been used for washing dirty overalls and other very dirty clothing, which 60 gasoline has been passed through the purifying system, but which gasoline has not been redistilled.

It is to be understood that the complete 65 purification of the gasoline with fuller's earth or like adsorbing material will require a cer-

tain minimum quantity of the fuller's earth per gallon of gasoline, depending upon the amount and character of impurities in the said gasoline. The clarifying material, such as fuller's earth, is accordingly fed to 70 the agitator tank preferably in a quantity regulated by the amount of gasoline being fed to the agitator tank, also the proportion of this material should bear a certain relation to the character and amount of the impurities. Accordingly the device as illustrated in Figs. 8 and 9 is preferably provided.

In this apparatus, power is supplied by means of the pulley 81 to a shaft 80 carrying a crank disc 82, to which is attached a crank 83, by means of a suitable stud 84. This stud 84 may be placed in any one of a number of holes 85 located at different distances from the center of the crank disc. 85 The other end of the crank 83 is connected to a variable stroke link 86. The variable stroke link is connected at a movable point in its length to the arm 87, the end of which is pivotally connected to the rock arm 88, 90 the upper end of which is rigidly secured to shaft 89. This shaft 89, which is suitably supported in rigid bearings (not shown) is provided at its other end with a bell crank lever 90, the outer end of which is in turn 95 connected with a link 91, to the end of another bell crank lever 92, carried upon the rotary shaft 58 above referred to, which in turn is rigidly connected to the rod carrying the float 57 in the float chamber which 100 is attached to the upper portion of the agitator tank. Accordingly rotation of the shaft 58 will move the arm 87 either to the right or left hand Fig. 9, thereby either lengthening or shortening the stroke of the 105 link 94 the upper part of which carries a pawl 95 engaging with the teeth of the ratchet wheel 96. The device is accordingly variable in its action on the ratchet wheel 96, depending upon the distance from the 110 center of the crank disc, at which the lower end of 83 is connected, and also upon the position of the float 57. In this manner the amount of clarifying material introduced to the hopper 45 at each revolution of the 115 crank disc 82 can be adjusted to meet the existing requirements, adjustment of 84 on 82 being manually made, depending upon the amount of dirt in the gasoline being treated, and the adjustment by the position of 87 120 relative to 86 being automatic depending upon the position of the float 57.

In Figs. 2 to 7 inclusive, I have illustrated details of the preferred construction of the centrifugal filter. The extractor basket 100 is of the ordinary well known type, being perforated with numerous small holes 101. Within this disc is placed a canvas filter bag 102. This filter bag is preferably slightly smaller than the interior dimensions of the 120

basket, and in the intervening space may be placed a felt filter. Located within the bag 102 and spaced therefrom is an inner filter bag, which is also preferably made of canvas or duck, preferably of a finer texture than that used in 102. This inner filter bag, 103 is preferably provided with a number of ruffles 104, which can be made in any suitable manner, for example, as shown in Fig. 6. In this modification a core 106 is placed against the inner surface of the filter bag, and a canvas strip 107 is placed around the same being stitched to the canvas at 108 and 109. Between 103 and 102 is a space in which may be located a filter felt of any desired construction. In order to impart a rotary motion to the liquid running into the rapidly rotating basket there is preferably provided a cycloid distributor 112 shown in Figs. 3 and 5. This cycloid distributor may be conveniently made by laying a piece of rope 113 upon the bottom of the inner filter bag and placing a strip of canvas 114 upon the same which canvas is stitched to the bottom of the inner filter bag as shown at 116. This distributor is preferably made in the form of a cross with the arms somewhat curved, as shown in Fig. 5, the rotation of the filter being in the direction of the arrow in Fig. 5. It is to be understood that a suitable cover (not shown) will be provided on the top of the centrifugal filter, in order to prevent evaporation.

I have referred above to the use of fuller's earth as the adsorbing material or clarifying material. The invention is not restricted to the use of this specific material, but numerous other materials acting in a similar manner may be employed, for example, pulverized talc or diatomaceous earth. It will be understood that the material taken up from the clothing being cleaned includes a number of constituents. Reference has already been made to oils and greases. In addition to these, the gasoline will take up numerous substances which possess odors, such as the dried perspiration, also dirt most of which will be found to exist in a substantially colloidal state in the cleaning liquid. The adsorbing material acts also as a coagulating agent coagulating the colloidal dirt, producing relatively large masses which will be precipitated in part and will in part be adsorbed by the coagulating agent.

The use of the coagulating adsorbing agent is entirely essential in the production of satisfactory results. If this is omitted, greases and fats and oils taken up by the gasoline will simply be carried back into the washing machine, and while a small quantity of the dirt could be separated by simple filtration, if the agitator tank and clarifying material supplied, were omitted, the result would not be satisfactory, since

the odors and greases would not be sufficiently removed from the clothing. I have shown from the lower end of the agitator tank as being hemispheric in shape. I find that this shape gives the most effective circulation in the lower part of said tank. The agitator tube in 52 is best supported by plates 53 which are set at an angle of from 45 to 60°, in order to give a rotary motion to the liquid passing upwardly around the agitator tube. The plate 53 on the left may slope backwards and the plate 53 may slope forwards. As a modified form of construction, instead of a single propeller 51, located in the lower part of the agitator tube 52, I may employ two propellers one just below the top of the agitator tube in addition to the one just within the bottom of the agitator tube which is illustrated in the drawing. These may be arranged to cause the liquids to travel in opposite directions, the one in the bottom drawing the liquid downwardly and the one in the top drawing the liquid upwardly, out of the agitator tube, and a number of holes can be provided in the agitator tube about midway of this height, so that the liquid in the upper part of the agitator tank will travel downwardly outside of the tube, through the holes above referred to and then upwardly inside of the tube, while the liquid in the lower part of the tank will travel in the direction shown by the arrows in Fig. 1.

The drawing illustrates a centrifugal filter as being the preferred form of filter for use in the system. However, I call attention to the fact that other forms of filters can be employed, although less advantageously, thus an ordinary filter press or a bag filter can be employed.

For supplying gasoline to the system, pipes may be provided as shown at 125 for introducing gasoline which needs to be purified or at 126 for introducing gasoline which is already sufficiently purified. Also a pipe 127 may be provided for drawing off the gasoline from the system for any desired purpose. These three pipes are supplied with suitable valves.

In addition to the advantages of the process as above described, the process possesses a very great economy in the amount of time required. The amount of time necessary for cleaning a given batch of goods by the process above described may amount to only one-third of the amount of time required according to the old system of working.

I have in the above description referred particularly to the use of gasoline as a cleaning fluid. It is, of course, to be understood that various other cleaning fluids may be likewise employed. For example, naphtha, benzine, liquid chlorides of carbon, or mixtures of such materials.

In the preferred operation, the liquid in

the agitator tank is preferably maintained a little above the top of the agitator tube 52.

In the above description, I have referred to continuous cyclic flow. Continuous flow is in many cases preferred, but in some instances it is advisable to employ an intermittent flow, that is to say, to run into the washer, a given amount of gasoline, or the like, then rotate the washer for a while, then draw off all the gasoline from the washer, then run in another charge of gasoline. This mode possesses some advantages, in that it is not necessary (especially when washing very dirty greasy articles, e. g. overalls) to run such a large amount of washing fluid through the washer and purifying system. In this event, a cyclic-intermittent flow is produced. The hand valves will be used in this system of working.

20 In some cases it is advisable to employ, along with the gasoline, dry-cleaner's soap. This does not necessitate any changes in the system, as already described.

25 In some instances the use of the adsorbing material may be omitted for a time, by passing the gasoline from the pipe 41 directly to the pipe 70 forming the inlet of the centrifugal separator. Thus, when articles are being washed which do not contain large 30 quantities of greases, it may be advisable to pass the gasoline direct from the tank 40 through the pipe 132 provided with valve 133, to the centrifugal separator, after the first portion of the gasoline, containing the 35 major part of the grease has been through the agitator tank.

40 In some instances the operation of the agitator tank, and if desired, also the centrifugal filter may be intermittent, that is to say the total supply of gasoline may be run through the agitator tank and centrifugal separator, into a suitable storage tank, from which the said gasoline is subsequently drawn to the washer.

45 The treatment of the dirty gasoline with the adsorbing material and subsequent filtration not only purifies the gasoline, but also acts to revivify the grease solubility of the gasoline or other washing media. It is of course to be understood that the total 50 amount of gasoline used can be drawn off from the system after being subjected many times to the adsorbing material, and redistilled, for the purpose of removing any 55 constituents which have been taken up with the gasoline which will not be removed by the adsorbing material.

The bags used in the centrifugal filter, both at 102 and 103 are preferably made 60 interchangeable, so that the same can be taken out of the centrifugal basket when desired and clean bags substituted therefor.

I claim:

1. In dry-cleaning, the herein described 65 process which comprises subjecting soiled

textile material containing greasy or oily material to the action of a volatile organic solvent which is substantially non-miscible with water; drawing off the solvent with accumulated impurities; agitating the said 70 solvent carrying impurities together with a solid material insoluble therein, which material possesses good adsorbing properties; separating the solid adsorbing material with accumulated impurities from the said solvent by filtration; and returning the solvent 75 free from said adsorbing material and adsorbed impurities in a substantially continuous manner to the first-mentioned step 80 of the process, until the said textile material has been cleaned to the desired extent.

2. In dry cleaning, the herein described process which comprises subjecting soiled textile material containing greasy or oily material to the action of a volatile organic 85 solvent which is substantially non-miscible with water; drawing off the solvent with accumulated impurities; agitating the said solvent carrying impurities together with fuller's earth; separating the fuller's earth 90 with adsorbed impurities from said solvent by centrifugal filtration; and returning the solvent free from said adsorbing material and adsorbed impurities in a substantially 95 continuous manner to the first-mentioned step 100 of the process, until the said textile material has been cleaned to the desired extent.

3. A system of apparatus comprising a washing machine, an agitator, means for 100 feeding solid material thereto, a separator, means for drawing off liquid from the washing machine, means for feeding the said liquid to the agitator, means for varying the amount of liquid and the amount of solid 105 material fed to the agitator according to the amount of the mixture therein, means for passing liquid from the agitator to the separator, and means for passing liquid 110 from the separator back to the washing machine.

4. A system of apparatus comprising a washing machine, an agitator, means for passing liquid from the washing machine to the agitator, means for feeding solid material thereto, means for regulating the amount of liquid and solid material fed to the agitator according to the amount of the mixture therein, a centrifugal filter, means for passing the mixture from the agitator 115 to the centrifugal filter, and means for passing the liquid from said filter back to the washing machine.

5. A system of apparatus comprising a washing machine, an agitator, means for 120 feeding solid material thereto, a separator; means for drawing off liquid from said washing machine, means for feeding the said liquid to said agitator, means for passing liquid from said agitator to said separator 125

and means for passing liquid from said separator back to said washing machine.

6. A system of apparatus comprising a washing machine, an agitator, means for feeding solid material thereto, a centrifugal filter; means for passing liquid from said washing machine to said agitator, means for passing liquid from said agitator to said centrifugal filter, and means for passing liquid from said filter back to said washing machine.

7. A system of dry cleaning apparatus comprising a washing machine, means for maintaining a substantially uniform depth of cleaning liquid in the washing machine, an agitator, means for passing liquid containing impurities from the washing machine to the agitator, means for feeding a solid material to the agitator, means for regulating the amount of liquid and solid material fed to the agitator, a centrifugal filter, means for feeding the mixture of solid material and liquid containing impurities from the agitator to the centrifugal filter, and means for feeding the liquid separated from the solid material and impurities from the filter into the washing machine.

8. A system of apparatus for clarifying gasoline containing impurities which comprises an agitator, means for feeding the gasoline with impurities to the agitator, means for feeding a solid adsorbent material to the agitator, means for regulating both feeding means according to the amount of the mixture in the agitator, means for feeding the mixture to a separator, and means for separating the gasoline from the solid material and the impurities.

9. A system of apparatus for clarifying gasoline containing impurities which comprises an agitator, means for feeding the gasoline with impurities to the agitator, means for feeding a solid adsorbent material to the agitator, means for simultaneously and automatically regulating both feeding means according to the amount of mixture in the agitator, means for feeding the mixture to a centrifugal filter, and means for leading the clarified gasoline from the filter.

50 10. A system of apparatus for clarifying a cleaning fluid comprising an agitator, means for feeding the cleaning fluid with contained impurities to the agitator, means for feeding a solid material which is a good adsorbent of the impurities to the agitator, means for regulating both feeding means in accordance with the amount of the mixture

in the agitator, and a centrifugal filter for separating the clarified cleaning fluid from the solid material and adsorbed impurities. 60

11. In dry cleaning, the herein described process which comprises subjecting soiled textile material containing greasy or oily material to the action of a volatile organic solvent which is substantially non-miscible with water; drawing off the solvent with accumulated impurities; agitating the said solvent carrying impurities together with a coagulating adsorbent agent; separating the adsorbent agent with adsorbed and coagulated impurities from the solvent by filtration; and returning the solvent free from said adsorbing material and impurities in a substantially continuous manner to the first-mentioned step of the process, until the textile material has been cleaned to the desired extent. 75

12. In dry-cleaning, the herein described process which comprises subjecting soiled textile material containing greasy or oily material to the action of a volatile organic solvent which is substantially non-miscible with water; drawing off the solvent with accumulated impurities; agitating the said solvent carrying impurities with an adsorbent agent; automatically measuring the amount of the adsorbent agent; separating the adsorbent agent with adsorbed impurities from the solvent by centrifugal filtration; and returning the solvent free from said adsorbing material and impurities to the first mentioned step of the process, until the textile material has been cleaned to the desired extent. 85

13. A system of apparatus comprising a washing machine, an agitator, a separator, means for drawing off liquid from the washing machine, means for feeding the said liquid in measured quantities to the agitator, means for feeding an adsorbent to the agitator, means for feeding the mixture to the separator, and means for feeding the purified liquid back to the washing machine. 95

14. A process for the recuperation of dry cleaning fluids which comprises mixing therewith a suitable agent for the coagulation of the colloid impurities, agitating the mixture, and filtering the fluid from the coagulating agent and the coagulated impurities. 105

In testimony whereof, I have hereunto subscribed my name.

JAMES T. FENTON.
